UNITED STATES PATENT OFFICE.

GIPP M. BREWER, OF SYLVIA, KANSAS.

WASHING-MACHINE.

1,242,765.

Specification of Letters Patent.

Patented Oct. 9, 1917.

Application filed May 25, 1916, Serial No. 99,878.

To all whom it may concern:

Be it known that I, GIPP M. BREWER, a citizen of the United States, residing at Sylvia, in the county of Reno and State of 5 Kansas, have invented a new and useful Washing-Machine, of which the following is a specification.

The present invention relates to an improvement in washing machines of that 10 type wherein pounders are employed.

An object of the invention is to provide a washing machine with an improved mechanism which not only reciprocates the pounder vertically in the receptacle, but 15 which also turns the pounder in one direction, and then reverses the direction of turning, so as to not only obtain the usual pounding of the clothes, but to also effect the striking of the pounders in a new position 20 upon each descent of the pounders and prevent the winding of the clothes about the pounders.

Another object of the present invention is to provide an operating means for the 25 pounder which embodies an improved yielding connection for taking up the variations in the height of the clothes collected beneath the pounder.

A further object of the present invention 30 is to provide a simplified mechanism for alternately raising and lowering a pair of spaced apart pounders, and providing a mechanism which also reciprocates the pounders in opposite turning directions during the raising and lowering of the same.

Other objects and advantages of this invention will be brought out in the following specific disclosure of the present preferred embodiment, the same being 35 illustrated in the accompanying drawings, wherein—

Figure 1 is a side elevation, partly in section taken through a washing machine constructed in accordance with the present 40 invention.

Fig. 2 is an end elevation, partly in section, of the same, the dotted lines showing the cover raised and the position of the mechanism carried by the cover.

Fig. 3 is a detail enlarged perspective view of one of the pounder connections.

Fig. 4 is a top plan view of the reversible driving means adjusted for turning the pounder in a clockwise direction, as indi-

cated by the arrow, the view showing the mechanism in an intermediate position.

Fig. 5 is a similar view showing the mechanism in one of its extreme positions and wherein the pounder has been advanced in the direction indicated by the 60 arrow.

Fig. 6 is a similar view showing the pin engaging the trip finger, and the subsequent reverse positioning of the feeding pawls to turn the plunger in an opposite or 65 anti-clockwise direction, as indicated by the arrow.

Fig. 7 is a bottom plan view of the same, showing the engagement of the pin against the trip finger.

Fig. 8 is a side elevation of the turning mechanism for the pounder, the parts being adjusted as shown in Fig. 4.

Fig. 9 is a vertical central section, taken through the turning mechanism, and showing the pivotal mounting of the pawl block.

Fig. 10 is a fragmentary top plan view of the rock shaft and the adjacent ends of the rock arms connected thereto.

Referring to these drawings, wherein like 80 parts are designated by similar numerals of reference throughout the several views, 10 designates a receptacle which may be of any desired shape and size, but which is shown in the present instance as being rectangular 85 in shape and elongated so as to provide a compartment in each end of the receptacle. The receptacle has a cover 11 hinged along one edge thereto and adapted to be swung laterally up into the dotted line position 90 shown in Fig. 2 for opening the receptacle. The ends of the receptacle 10 may be provided with flanges or bars 12 which extend substantially vertically from the top of the receptacle for supporting a wringer or the 95 like.

The cover 11 carries pounders 13 and the mechanism required for operating the same according to this invention. At a point intermediate the ends of the cover 11 is placed 100 a pair of upstanding bearing blocks 14, which are spaced apart transversely and which have journaled therein a rock shaft 15. The rock shaft 15 extends at its opposite ends beyond the bearing blocks 14, and 105 has on one of said projecting ends a preferably upstanding handle 16, and upon the opposite extending end an upwardly extend-

ing ear 17. To the ear 17 is pivotally connected the upper forked end 18 of an arm 19 which carries upon its lower end a weight 20. The arm 19 and the weight 20 comprise a pendulum which is attached to the rock shaft 15 to maintain the steady oscillation of the same. The fork 18 of the pendulum arm has its opposite sides extending upwardly against the opposite sides of the ear 17, so as to provide a substantially rigid connection between the pendulum arm 19 and the rock shaft 15.

The rock shaft 15 is provided between the bearings 14 with a socket casting 21, which is secured against the lower side of the rock shaft 15 and which extends beyond the opposite sides of the rock shaft toward the opposite ends of the receptacle 10. The ends of the casting 21 are recessed to provide opposed sockets adapted to receive therein the inner ends of arms 22, the same being hinged in the sockets by transverse bolts 23. These bolts 23 pass through upstanding flanges at the opposite edges of the casting 21 to hingedly support the inner ends of the arms 22 in the sockets. The bottoms of the sockets constitute stop or supporting shoulders 24 upon which the arms 22 rest to limit their downward movement.

30 A post 25 in the form of a bolt passes upwardly and centrally through the casting 21 and the rock shaft 15 and is threaded upon its upper extremity. A leaf spring 26 is apertured intermediate its ends for engagement over the post 25. The opposite ends of the leaf spring 26 slidably rest upon the upper faces of the arms 22 adjacent the outer ends of the same. A spring 27, preferably of the helical type, surrounds the post 25 and bears at its lower end upon the leaf spring 26. An adjusting nut 28 is threaded upon the upper end of the post 25, and bears downwardly upon the upper end of the helical spring 27, to compress the same 45 against the leaf spring 26 and vary the pressure of the same upon the outer ends of the arms 22.

Each end of the cover 11 is provided with a vertically extending plunger rod 29. The 50 rod 29 is mounted for vertical movement through the cover 11, and carries upon its lower end a pair of the pounders 13, which are of the cone type and which are connected together and to the lower end of rod 55 29 by cross pieces 30. In Fig. 1 it will be noted that the upper ends of these cone shaped pounders 13 have small openings 31 near their upper ends which are adapted to permit the escape of air from the tops of the 60 cones. These air openings 31 are preferably located at the inner sides of the cones beneath the upper cross piece 30.

The cover 11 is also provided near each end with an upstanding bracket comprising 65 an end arm 32 and a lateral arm 33. These

arms are joined together at their upper ends and provide a bearing and a support for the upper end of the plunger rod 29. Within the bracket, and adjacent the upper end of the plunger rod 29, is a pair of vertically 70 spaced apart collars 34 fixed upon the rod in any suitable manner, as by sweating, or the like, and between these collars is placed a loose plate 35 constituting a connecting plate. The plate 35 is provided with diametrically and oppositely extending pins 36 and 37, the pin 37 being relatively long and projecting laterally into a vertically extending slot 38 formed in the lateral arm 33. This pin 37 engages in the slot to hold the 80 plate 35 from turning with the plunger rod 29.

The plate 35 is provided with a pair of links 39 and 40, which are hinged at their upper ends on the pins 36 and 37, and which 85 preferably extend downwardly and have pivotal connection at or near their lower ends to the outer forked portions 41 of the arm 22. The outer end of the arm 22 is forked to receive the plunger rod 29 therein 90 when the arm 22 is moved downwardly, and to provide an arm or extension at each side of the plunger rod 29 for pivotal engagement with the spaced apart links 39 and 40. This construction is provided upon each end 95 of the cover 11, so that each arm 22 has a plunger rod connected to its outer end. The plunger rods 29 are free to turn within the plates 35, and the plates are held from turning by the relatively long pins 37 which engage in the vertical guiding slots 38.

By rocking the shaft 15, the arms 22 are alternately raised and lowered, so as to carry therewith the plunger rods 29. When the clothes in the receptacle 10 pack beneath one of the pounders 13, that pounder when moved downwardly will be brought into engagement with the clothes before the pounder reaches the limit of its downward stroke. In this instance the spring 27 is so 110 adjusted as to permit the leaf spring 26 to yield under such conditions and prevent the breakage or straining of any parts of the machine.

From the above description, it will be 115 noted that the structure so far permits the plunger rods 29 to rotate freely within the plates 35, so as to carry the pounders 13 into various new positions, as desired. The reciprocation or swinging of the lower ends 120 of the links 39 and 40 is taken advantage of in the present structure to positively and consecutively advance the pounders in one direction, and to then automatically reverse the turning of the pounders to prevent the winding of the clothes thereabout.

Each plunger rod 29 has fixed to it a toothed wheel 42. The toothed wheel 42 is of the double ratchet type, or that type which may be operated by pawls which ex- 125

tend in opposite directions, so as to drive the wheel first in one direction and then in the opposite direction. Rotatably mounted on each plunger rod 29 immediately above the wheel 42 is a bell crank lever having arms 43 and 44. The arm 43 when in intermediate normal position, as shown in Fig. 4, extends outwardly from the plunger rod 29 laterally of the receptacle 10, and is provided with a slot 45 which extends radially in the arm and which receives therein the lower end of a pin 46 which projects downwardly from the lower end of the link 40. The opposite arm 44 of the bell crank lever 15 extends substantially at right angles from the arm 43, and extends toward the adjacent end of the receptacle 10. This arm 44 pivotally carries upon its outer end a pawl block 47 adapted to swing in a horizontal 20 plane beneath the arm 44, and which has an arm 48 projecting laterally therefrom toward the arm 43.

The outer ends of the arms 43 and 48 are connected together as best shown in Fig. 8, 25 by a rod 49 which is hinged to the end of the arm 43, but which slidably engages at its opposite end through an eye 50 on the outer end of the arm 48. A head 51 is formed on the outer end of the rod 49 for engagement 30 against the eye 50 to prevent the sliding of the rod 49 from the eye. In this manner, the outer ends of the arms 43 and 48 are tied together but are permitted to move toward each other into the position shown in Figs. 35 6 and 7. An expanding spring 52 surrounds the rod 49 between the arm 43 and the eye 50, so as to yieldingly force the arms 43 and 48 apart. By this arrangement and construction, the spring 52 yieldingly holds the 40 pawl block 47 in either one of two positions, one position with one end approaching the teeth of the double ratchet wheel 43, while in the other position the opposite end approaches said wheel.

A one piece pawl 53 is hinged in the inner side of the block 47 intermediate its ends and projects slightly beyond the ends of the block and is turned in to provide a nose on each end of the pawl. The block 47 also 50 has a spring 54 in each end which bears against the adjacent end of the pawl 53, the springs being of substantially equal strength to yieldingly hold the pawl 53 in substantially true longitudinal alinement in the block 47, so that the springs 54 hold the pawl in position to operate from either end thereof.

For the purpose of rocking the block 47 to engage the opposite ends of the pawl 53 55 alternately with the teeth of the wheel 42, a trip finger 55 projects inwardly toward the plunger rod 29, from the lower side of the block 47 and lies in the path of a downwardly projecting pin 56, which is carried by the wheel 42. When the arm 43 is moved to the left from the position shown in Fig. 5, the trip finger 55 will engage the pin 56, as shown in Fig. 6, and rock the pawl block upon the arm 44 to swing the arm 48 inwardly against the tension of the spring 52, reversing the action of the pawl.

When the device is in use, clothes may be placed in the opposite ends of the receptacle 10 beneath the sets of pounders 13. The handle 16 is grasped and reciprocated back and forth to rock the shaft 15 and swing the pendulum or weight 20. This movement of the shaft 15 swings the oppositely extending arms 22 in a vertical plane, the forked portions 41 of the arms moving in arcuate paths. The arms 22 are thus alternately raised and lowered, and transmit their motion through the links 39 and 40 to the plunger rods 29. When one of the plunger rods 29 is moved down, it forces the pounders 13 against the clothes in the receptacle 10, and the weight 20, by its momentum, continues its stroke and thus forces the pounders 13 against the clothes. If sufficient resistance is offered by the clothes, the arm 22 will be arrested in its downward movement, and the springs 26 and 27 will yield, so as to permit the slight rocking of the shaft 15 while the arm 22 is held stationary.

As the outer ends of the arms 22 travel in arcuate paths, and as the links 39 and 40 are hinged to the plates 35 which are carried upon the plunger rods 29, the ends of the links which are connected to the arms 22 swing back and forth through the transverse planes of the plunger rods, so that the elongated links 40 carry the pins 46 thereof back and forth in paths extending longitudinally of the receptacle 10. This movement of the pins 46 swings the arms 43 of the turning devices for the plunger rods and effects the intermittent rotation of the latter.

In Fig. 4 of the drawings, the turning device is shown with its pawl 53 engaging with the ratchet wheel 42 to advance the ratchet wheel in a clockwise direction, as shown by the arrow, when the arm 43 is moved to the left. The arm 43 is integral with or rigidly attached to the arm 44, so that the swinging of the arm 43 to the left advances the arm 44 which carries the pawl block 47 to force the pawl 53 against the ratchet wheel 42 and advance the latter. When the arm 43 is again moved to the right, the arm 44 draws the pawl block 47 in a reverse direction, and the end of the pawl 53 rides over the teeth of the ratchet wheel 42 back to the position shown in Fig. 4, the pin 56 having been advanced however. The frictional contact of the plunger rod 29 with its bearings and with the plate 35 is sufficient to overcome the friction of the pawl 53 as it is drawn backwardly over the teeth of the ratchet wheel 42, so that the

plunger rod 29 remains in its advanced position during the retraction of the pawl 53 to obtain a new grip upon the wheel 42.

The arm 48 is swung outwardly away from the arm 43 and the spring 52 holds the arm 48 yieldingly in this position, as shown in Fig. 4. When the arm 48 is swung outwardly, the pawl block 47 is swung about its pivotal support upon the outer end of the arm 44 and the far end of the pawl 53 is advanced into the path of the teeth of the wheel 42. The spring 54 holds the far end of the pawl in contact with the teeth.

After the plunger rod 29 has practically completed a turn, the pin 56 will have been carried from the position shown in Fig. 4, to the position disclosed in Fig. 5, in which position the pin 56 engages the trip finger 55 and rocks the pawl block 47 upon the arm 44 to swing the arm 48 inwardly against the tension of the spring 52. Fig. 6 shows the position of the pin 56, the trip arm 55, and the pawl block 47 after the latter has been tripped and the arm 48 has been thrown inwardly against the arm 43. It will be noted from Fig. 8 that the arms 43 and 48 lie in substantially the same horizontal plane, so that the edge of the arm 43 constitutes a stop for the arm 48, as shown in Fig. 6. The spring 52 is now permitted to again expand and hold the arm 48 against the arm 43. In this position the far end of the pawl 53 is raised out of the path of the teeth of the wheel 42, while the adjacent nose of the pawl is swung into the path of the teeth.

It is thus seen that when the arm 48 is swung from the position shown in Fig. 4 to the position shown in Fig. 6, the wheel 42 and the plunger 29 can be advanced in an anti-clockwise direction, as shown by the arrow in Fig. 6, so that a reverse turning of the plunger is had. The plunger turns in this anti-clockwise direction until the pin 56 reaches the opposite side of the trip finger 55 when the pawl block 47 is again swung into the position shown in Fig. 4. By thus oscillating the plunger rod 29 by turning it first in one direction, and then in an opposite direction, the pounders 13 not only obtain a new position each time they are forced downwardly into the receptacle, but they are also prevented from winding into the clothes which are in the receptacle. The lateral arms 33 hold the plates 35 from turning with the plunger rods 29, so that there is no binding action or unnecessary friction between the plunger rod and the links 39 and 40.

From Fig. 2, it will be noted that when the cover 11, with the plunger rods and the operating mechanism connected thereto is swung down into closed position, the forked upper end 18 of the pendulum engages against the opposite sides of the upstanding

ear or lug 17 and braces the opposite sides of the ear or lug 17, so that the pendulum regulates the swinging of the rocking members which includes the shaft 15 with its arms 22 and its spring mechanism. When the cover 11 is raised into the position shown in dotted lines in Fig. 2, the lug 17, which is pivoted at its upper end to the forked upper end 18 of the pendulum, swings laterally away from the receptacle 10 and moves the weight 20 outwardly from the hinged end of the cover 11 so that the effective weight of the pendulum upon the cover is increased to counter-balance the same to a large extent and thus decrease the resistance of the cover 11 to its swinging upwardly into open position. The dotted lines in Fig. 2 show the position of the pendulum which is advanced laterally from the receptacle 10, so as to hold the cover open and counter-balance it.

The rocking member is connected at its ends to the plunger rods by means of the links 39 and 40, the links 40 actuating the turning means for the plungers which comprises the toothed or double ratchet wheels 42 and the pawls with their parts. The pins 56 and the trip fingers 55 provide automatic reversing means for the turning means.

What is claimed is:—

1. In a mechanism of the character described, a reciprocating rod, a ratchet wheel fixed to said rod for rotating the same and adapted to reciprocate therewith, a lever pivoted on said rod adjacent to said ratchet wheel, a pawl block pivoted to said lever and provided with a double pawl adapted to engage said wheel to rotate the same in opposite directions, means upon said wheel for actuating said block to reverse the direction of rotation of the ratchet wheel, and means connected to said rod and lever for actuating the same.

2. In a mechanism of the character described, a reciprocating rod, a ratchet wheel fixed to said rod and movable therewith, a pawl also mounted upon said rod and adapted to engage said ratchet for rotating the rod, devices for actuating said pawl, a link pivoted to said rod and in engagement with the devices for actuating the pawl, and means for imparting to said link a reciprocatory and swinging movement whereby the rod is reciprocated as well as rotated.

3. In a mechanism of the character described, a reciprocating rod, coöperating devices mounted upon said rod for rotating the same, a link connected to the rod at one end and coöperating with said devices at the other end for actuating the same and a swinging arm connected to said link for causing the same to reciprocate the rod as well as rotate the same.

4. In a mechanism of the character de-

95

- scribed, a rocking member including an outstanding arm adapted to swing at its outer end in a curved path, a movable rod, a link hinged at one end upon the rod and adjacent to its opposite end to the outer end of said arm to swing the link upon the movement of the rod and the arm, turning means carried by the rod and having connection with the free end of said link to actuate the turning means upon the swinging of the link, and automatic reversing means carried by the turning means to rotate the rod first in one direction and then in an opposite direction.
5. In a mechanism of the character described, a rocking member, a vertically movable rod, a link connecting the rod to one end of said member to raise and lower the rod and to swing the link in a horizontal path, a ratchet wheel fixed to the rod, a lever hinged to the rod adjacent the ratchet wheel and having connection with the free end of said link to swing the lever upon the vertical movement of the rod, and a pawl connected to said lever for engagement with the ratchet wheel to advance the same upon the movement of the lever in one direction and to ride freely over the teeth of the ratchet wheel upon the movement of the lever in an opposite direction to obtain a new grip upon the ratchet wheel.
10. In a mechanism of the character described, a rocking member, a rod at each end of said member, a link between each rod and the adjacent end of the member, a ratchet wheel on each rod, levers on the rods adjacent the ratchet wheels and having connection with the free ends of the adjacent links, pawls on the levers for engagement with the ratchet wheels and adapted to advance the same upon the movement of the links in one direction, and reversing means carried by the rods for reversing the engagement of the pawls with the ratchet wheels to advance the ratchet wheels in an opposite direction.
15. In a mechanism of the character described, a rocking member, a rod, a plate mounted for rotation upon the rod and being held from longitudinal movement thereon, laterally extending pins at the opposite sides of the plate, a pair of links each hinged at one end to the opposed pins and having hinged connection at their opposite ends to said rocking member, a bell crank lever hinged upon said rod adjacent the lower ends of said links and having a slot in one arm thereof to receive the end of one of said links therein for rocking the bell crank lever on the rod upon the vertical movement of the same, a double ratchet wheel fixed to the rod adjacent the bell crank lever, a pawl block hinged upon the opposite arm of the bell crank lever, a pawl in said pawl block having a nose at each end, an arm on said pawl block projecting toward said slotted arm of the bell crank lever, a spring between the ends of said slotted arm and said pawl block arm to urge said arms apart and yieldingly hold the pawl block in oppositely swung positions, whereby said opposite noses of the pawl are adapted to engage alternately with the teeth of said ratchet wheel to drive the same in opposite directions, and means on the ratchet wheel for engagement with the pawl block to shift the same into an opposite position upon each revolution of the ratchet wheel.
20. In a mechanism of the character described, a rocking member, a rod, a link hinged at one end to the rod and having hinged connection near its opposite end to said rocking member to vertically reciprocate the rod upon the movement of the rocking member and to swing the free extremity of said link in a path intersecting the transverse plane of the rod, a toothed wheel fixed to the rod, a bell crank lever hinged to the rod above said wheel, a pawl block hinged to one end of the bell crank lever and having an arm at one end extending toward the opposite end of the bell crank lever and having a trip finger at its under side projecting beneath said wheel, a spring between said opposite end of the bell crank lever and said arm on the pawl block to urge the arms apart and yieldingly hold the pawl block arm outwardly from the bell crank lever and inwardly against the same to retain the pawl block in oppositely swung positions, a pin projecting downwardly from the wheel for engagement against the opposite sides of said trip finger to shift said pawl block, and a double nosed pawl arranged in said block for alternate engagement at its ends with said wheel to advance the same in opposite directions.
25. In a mechanism of the character described, a rocking member, a bracket at one end of the rocking member and having a lateral arm provided with a vertical slot therein, a rod mounted in the bracket, a plate rotatably mounted on the rod and held from longitudinal movement thereon, oppositely extending pins carried at the sides of said plate, one of said pins being elongated and projecting through the vertical slot in said lateral arm to hold the plate from turning about the rod, a pair of links hinged at one end upon said pins and having hinged connection at their opposite ends to said rocking member for vertically reciprocating the rod, and turning means mounted on the rod and having connection with the lower end of one of said links to actuate the turning means upon the vertical reciprocation of the rod.
30. In a mechanism of the character described, a rock shaft journaled in suitable bearings, a casting secured to an intermediate portion of the rock shaft and having

- laterally extending sockets open at their tops and providing supporting shoulders in their bottoms, a pair of arms hinged at their inner ends in said sockets and adapted to 5 extend oppositely and outwardly from the rock shaft and bear on said supporting shoulders, a post projecting upwardly from the rock shaft in line with said arms, a leaf spring engaging over said post at its intermediate portion and having its opposite ends bearing against the upper faces of 10 said arms to yieldingly hold the same against said shoulders, a coiled spring surrounding the upper end of the shaft and bearing on said leaf spring, an adjusting nut mounted on the upper end of said post for adjustably urging said coiled spring against the leaf spring to increase the tension of the same on said arms, and a plunger rod connected to the outer end of each 15 of said arms and adapted to be raised and lowered thereby, said coil and leaf springs permitting the yielding of said arms upon the binding of said plunger rods.
11. In a mechanism of the character described, a plurality of rods, a rock shaft journaled in suitable bearings, a pair of oppositely extending arms pivotally connected to the opposite sides of the rock shaft, shoulders outstanding from the rock shaft beneath said arms to support the same in outstanding relation to the rock shaft, a leaf spring bearing at its opposite ends upon the upper faces of said opposed arms, said 20 arms having connection with said rods to alternately reciprocate the same in a vertical direction, and means carried by the shaft engaging said leaf spring to vary the tension thereof and to provide a yielding connection between the rock shaft and said rods.
12. In a mechanism of the character described, a movable rod, a rock shaft, an arm hinged to the rock shaft and extending outwardly therefrom and having engagement 25 with said rod to operate the same, a spring connected to the rock shaft and bearing at its end upon said arm to urge the same downwardly, and a shoulder carried by the rock shaft and extending beneath the arm to limit the downward movement of the same, said spring and said arm being adapted to yield upwardly upon impact of the rod to prevent jar upon the machine.
13. A mechanism of the character described comprising a plurality of vertically movable rods, a pounder on the lower end of each rod, a rock shaft journaled midway between the rods, oppositely extending arms 30 carried by the rock shaft, a plate mounted to turn on each rod and having outstanding pins at its opposite sides, a pair of links hinged at one end upon the pins of each plate and having pivotal connection at their 35 opposite ends with said arms to vertically reciprocate the rods upon the rocking of the shaft, a ratchet wheel on each rod, a bell crank lever on each rod having one end connected to the adjacent link to swing the bell crank lever back and forth upon the movement of the link, a shiftable pawl carried upon the opposite arm of each bell crank lever and having a nose at each end for engagement one at a time with the ratchet wheel to advance the ratchet wheel in 40 opposite directions, and automatic means between the ratchet wheel and the shiftable pawl for shifting the latter to alternate the positions of said noses and change the direction of operation of the pawl upon 45 each predetermined advancement of the ratchet wheel.
14. In a washing machine, a receptacle having a hinged cover, a plunger rod carried by the cover and projecting into the receptacle, a rocking member mounted on the cover and having connection with the plunger rod and including a rock shaft journaled transversely across the cover midway between its ends and having one end projecting beyond the hinged edge of the cover and beyond the adjacent side of the receptacle, said projecting end having an upstanding ear thereon, a pendulum having a forked upper end engaging about the ear 50 and having pivotal connection with the upper end thereof, said pendulum, when the cover is closed, being adapted to hang down close against the receptacle and said forked end being adapted to extend substantially in parallelism with and in engagement against the opposite sides of the ear to brace the pendulum upon the rock shaft, said ear being adapted to be swung down into substantially horizontal position upon the raising 55 of the cover to lower the pendulum and move it outwardly from the receptacle to increase the leverage of the pendulum on the cover and counter-balance the same.
15. In a mechanism of the character described, a reciprocating plunger, a ratchet wheel fixed to said plunger for rotating the same, a bell crank lever pivoted upon said plunger adjacent said wheel, a pawl block pivoted to one arm of said bell crank lever 60 and provided with a double pawl resiliently mounted thereon adapted to engage said wheel for rotating the same in opposite directions, a spring connecting one end of said pawl block with the other arm of said bell crank lever, devices upon said pawl block and ratchet wheel adapted to periodically engage each other to swing the pawl block into position to reverse the direction of rotation of the ratchet wheel, and means for 65 actuating said plunger and said bell crank lever.
16. In a washing machine, a hinged cover, operating mechanism mounted upon said cover comprising an oscillating shaft pro- 70 75 80 85 90 95 100 105 110 115 120 125 130

vided with a handle and a pendulum pivoted on an axis parallel with the axis of the hinge and adjacent thereto whereby when the cover is raised the pendulum will retain the same in such raised position and when closed serves to retain the handle in vertical position.

In testimony, that I claim the foregoing as my own, I have hereto affixed my signature in the presence of two witnesses.

GIPP M. BREWER.
